UNITED STATES PATENT OFFICE.

LOGAN WILLARD MULFORD, OF NARBERTH, PENNSYLVANIA.

SIDEWALK, VAULT-LIGHT, FLOOR-LIGHT, AND SKYLIGHT CONSTRUCTION.

1,167,917.

Specification of Letters Patent. Patented Jan. 11, 1916.

Application filed July 6, 1914. Serial No. 849,325.

To all whom it may concern:

Be it known that I, LOGAN WILLARD MULFORD, a citizen of the United States, residing at Narberth, county of Montgomery, State 5 of Pennsylvania, have invented a new and useful Sidewalk, Vault-Light, Floor-Light, and Skylight Construction, of which the following is a specification.

In sidewalk, vaultlight, floorlight, and 10 skylight construction, as ordinarily manufactured, considerable difficulty has arisen and a large amount of expense has been involved in replacing the lenses which have become broken or chipped, due to the unequal expansion and contraction of the 15 different materials of which the construction is made up, abuse, etc., since it has been necessary to chip out the broken glasses or lenses before the new lenses can be cemented 20 in position.

In accordance with my present invention, I have devised a novel vaultlight and similar construction, wherein a chipped or broken lens may be readily removed by 25 breaking out the same with a hammer or similar device, and thereafter a new lens may be readily and quickly screwed in position.

With the above and other objects in view, 30 which will more clearly hereinafter appear in the detailed description, my invention consists of a novel sidewalk, vaultlight, floorlight, and skylight construction, wherein the lenses may be readily replaced by other 35 lenses of the same size.

It further consists of a novel construction 40 of a lens, a novel construction of a band, adapted to be placed in threaded engagement with said lens, and said band being interlocked with the concrete or other binding material employed, so that both its upper and lower portions are embedded in the concrete at a desired distance from the upper and lower surfaces of the construction.

45 It further consists of a novel construction of a band, having its bottom portion laterally deflected to form a plurality of flanges, which interlock with the concrete, and prevent the relative rotation of the 50 band with respect to the concrete.

It further consists of other novel features of construction, all as will be hereinafter fully set forth.

For the purpose of illustrating my invention, I have shown in the accompanying 55 drawings one form thereof which is at present preferred by me, since the same will give in practice satisfactory and reliable results, although it is to be understood that the various instrumentalities of which my 60 invention consists can be variously arranged and organized and that my invention is not limited to the precise arrangement and organization of these instrumentalities, as 65 herein shown and described.

Figure 1 represents a bottom plan view 70 of a portion of a sidewalk, vaultlight, floorlight, and skylight construction, embodying my invention. Fig. 2 represents a sectional elevation thereof. Fig. 3 represents a 75 sectional elevation, on an enlarged scale, of a portion thereof. Fig. 4 represents a perspective view of a band employed. Fig. 5 represents a perspective view of one type of lens employed.

Similar numerals of reference indicate corresponding parts in the figures.

Referring to the drawings: My present invention is more particularly directed to the novel construction of lens employed and 80 the novel manner of interlocking the same with respect to the lenses or tiles and the concrete, it being understood that the band is interlocked and positioned in the concrete in such a manner that when a lens has been 85 removed, it is simply necessary to screw a new lens into place, and my invention is not limited to any special construction of the lenses or tiles, nor to any special type of reinforcement or frame-work for the concrete 90 or other binding material.

1 designates reinforcing rods or a frame-work of any desired type, which are embedded in the concrete or other binding material 2 employed.

95 3 designates a band, which, preferably, consists of an integral piece of material, and the material employed for making this band may vary widely in practice. The band 3 has its side wall corrugated to form the 100

threads 4, and the bottom of said band 3 is cut away, as indicated at 5, and the remaining portion laterally deflected to form the laterally extending flanges 6, which, when 5 the construction is completed, are firmly interlocked with the concrete 2, and prevent any unscrewing of the band with respect to the concrete, due to the vibration and shocks to which the completed construction is subjected in practice.

7 designates a lens or tile of any desired or conventional type, but which, in the present instance, I have illustrated as having a smooth outer periphery near its upper end, 15 as at 8, a threaded portion 9, and the outer periphery at its lower end is outwardly flared or beveled, as at 10.

When the parts are to be assembled, a cement or other material 11 is placed around 20 the threads 9 and the lens 7 is screwed into the band 4, and in practice, I preferably employ a cement, which will remain plastic. Each lens is provided in its bottom face with a rectangular shaped recess 12, in order that 25 a tool may interlock therewith when the lens is to be inserted in position. In practice, the bars 1 are inserted in position in the form illustrated, it being understood that cross bars are also employed, the lenses 30 with the bands thereon are supported in alined position, and then the concrete 2 is poured in, so as to interlock with the grooves of the band and the flanges 6, so that any movement of such band is positively pre- 35 vented, as soon as the concrete is set. When it is desired to insert a new glass or lens in position, it is simply necessary to knock out the old lens with a hammer, place the plastic cement or other equivalent material around 40 the threads of the new lens, and then screw the same into position, and thereafter finish the top surface of the concrete around the lens with a finishing compound, which will cause a watertight joint to be formed 45 with the lens at such point.

Owing to the novel construction and arrangement of the flanges 6, the concealed band is firmly interlocked with the concrete and is held in such a position that a new 50 lens of the same size as the old lens may be inserted.

It will be seen that the upper portion of the band terminates a desired distance beneath the top face of the completed construction, and the lower portion of the band terminates a desired distance above the bottom face of the construction, so that the band is entirely concealed and is not exposed to the elements, so that the durability of the 55 life of the same is largely increased and a waterproof joint can be formed on the tread surface of the construction in proximity to the lenses.

I am aware that it has heretofore been

proposed in the patent to Jacobs, No. 488,122, 65 to employ in a vaultlight construction, a band which surrounds the glass, but in such construction, the glass cannot be replaced in the same band and the function of the jacket is entirely different from that of my present 70 invention, since in my device, when it is desired to replace the glass, it is simply necessary to knock out the old glass and screw a new one into position.

I am also aware that it has heretofore 75 been proposed to employ a helical wire interlocking with a lens, but in such construction, when it is desired to replace a lens, it is necessary to employ a lens of a smaller 80 size, and as is apparent, my present invention is clearly differentiated from these prior constructions, and to none of these constructions of the prior art do I make my claim.

It will now be apparent that I have devised a novel and useful construction of a 85 sidewalk, vaultlight, floorlight and skylight construction, which embodies the features of advantage enumerated as desirable in the statement of the invention and the above description, and while I have, in the 90 present instance, shown and described a preferred embodiment thereof which will give in practice satisfactory and reliable results, it is to be understood that the same 95 is susceptible of modification in various particulars without departing from the spirit or scope of the invention or sacrificing any of its advantages.

Having thus described my invention, what I claim as new and desire to secure by Letters Patent, is:-

1. A construction of the character stated, comprising a concrete body, threaded bands terminating within the body below the top and above the bottom thereof and interlocked with the body, the bottom of said bands having a plurality of flanges extending laterally therefrom and interlocked with the concrete, and lenses having threads to engage the threads of said band, and said body being constructed to permit the insertion of a lens from the under side of the body.

2. A construction of the character stated, comprising a concrete body having reinforcements therein, bands interlocked with the body and each consisting of an integral piece of material having portions of its side wall deflected to form threads and having portions cut away at its bottom to form 120 a plurality of flanges which are outwardly deflected and interlocked with the concrete body, the upper ends of said bands terminating beneath the top of said body and the lower ends of said bands terminating 125 above the bottom of said body, lenses having intermediate their ends threads to engage the threads of said bands, plastic cement

between said lenses and said bands, the lower end of a lens having an inwardly converging side wall and a portion of said concrete body beneath the flanges of a band 5 forming an inwardly converging side wall with which the converging side wall of a lens engages, and said lenses being adapted

to be inserted into position from the under side of said concrete body.

LOGAN WILLARD MULFORD.
